UNITED STATES PATENT OFFICE

ROBERT JEFFERSON CATLETT, OF NORTH TOPEKA, KANSAS

PROPELLING MECHANISM

Application filed August 20, 1927. Serial No. 214,327.

The present invention relates to a propelling mechanism designed particularly for use with aeroplanes, marine vessels, air motors, and the like.

5 I shall describe the invention as used with an aeroplane, since this will enable me to bring out all of the main advantages of the structure.

The purpose of the invention is to provide 10 a propelling mechanism which greatly simplifies the propellers now in use on aeroplanes of the helicopter type and which furnishes a more efficient traction propeller for an aeroplane when in flight, and makes it possible 15 for an aeroplane to sustain itself at a given altitude more effectively while in flight.

My improved mechanism greatly increases 20 the air displacement in both lineal and cubic feet when driven at a like speed to the present type of propeller. This is of great value as it makes it possible for the aeroplane to carry a great weight with less wing surface and further makes it possible for the aeroplane to carry considerable weight without planes.

25 This propeller mechanism, through the motion of its propeller blades, piles up a commotion or pressure of air behind it which gives it a firm backing to push against. The propeller mechanism makes possible vertical ascent and descent. It also makes it possible to remain stationary in any desired altitude or to go forward or rearward, upward or downward, at the will of the operator. The propeller mechanism is designed to operate to 35 the side of the aeroplane, thereby setting up less friction than the type of propeller now in common use.

The present type of propeller in common use throws a strong air current against the 40 body of the machine, and this energy which is used to overcome the resistance set up by the body is saved by the use of my improved propeller structure.

An important object of the invention is to 45 provide a propeller mechanism of this nature which is exceedingly easy to manipulate, one which is efficient and reliable in its operation, strong and durable, compact and convenient, and otherwise well adapted to the purpose 50 for which it is designed.

With the above and numerous other objects in view as the description proceeds, as will appear, the invention resides in certain novel features of construction, and in the combination and arrangement of parts as will be hereinafter more fully described and claimed. 55

In the drawing:

Figure 1 is a top plan view of an aeroplane embodying the features of my invention,

Fig. 2 is a longitudinal section through the 60 propeller mechanism,

Fig. 3 is an end elevation of one of the propeller frames,

Fig. 4 is a detail view through the adjusting mechanism of the propeller mechanism, 65

Fig. 5 is an enlarged end elevation showing 70 one of the frames and a diagram of the propeller blades in different positions of their cycles.

Referring to the drawing in detail, it will be seen that 5 designates the fuselage of an aeroplane, having the front wings 6 and rear wings 7. This type of aeroplane has been shown merely by way of example. A casing 8 is mounted in the body and a shaft 9 is journaled in the casing, and is operated exteriorly of the casing by a wheel 10 or in any other suitable manner. Interiorly of the casing, there is disposed on the shaft 9, a worm 75 11.

Bearings 12 and 13 are provided in the 80 fuselage 5 for rotatably receiving a pair of aligned hollow shafts 14, one on each side of the casing 8. Drive gears 15 are fixed on the inner ends of the shafts 14 and are operatively connected with suitable prime movers 16 which may be in the form of internal combustion engines, such as are now in common use. A frame 17 is mounted on the outer end 85 of each shaft 14. A shaft 18 is journaled thru the shafts 14 and through the casing 8 and has mounted thereon within the casing 8, a worm gear 19 meshing with the worm 11.

Pinions 20 are fixed on the outer ends of the 90 shaft 18, one adjacent each frame 17. A pair of intermediate pinions 18' are mounted for rotation on each frame 17 in mesh with the pinion 20. A pair of gears 21 are rotatably mounted on each frame 17 and are in mesh 100

with the intermediate pinions 18'. These gears 21 are located at the ends of their respective frames. A propeller blade 22 is operatively connected with each gear 21.

5 It will thus be seen that by rotation of the wheel 10 the angle of the blades 22 of each pair may be changed as desired. This is accomplished through the intermediacy of the worm 10, the worm gear 19, shaft 18, pinions 10 20 and 18' and gears 21. The pinions 20 and 18' and the gears 21 must be proportioned so that gears 21 make one-half rotation on their own axes each time the pinions 18' make one complete revolution around the pinion 20.

13 If the blades are disposed as is shown in full lines in Fig. 5, it will be seen that as the frames rotate in the direction indicated by the arrows, the blades will be fixed so as to tend to lift the aeroplane vertically. This 20 may be easily ascertained by following the cycles through which the blades revolve as is shown in dotted lines in the figure. However, if the blades are positioned in relation to each other as is indicated in Fig. 3, it will 25 be seen that the aeroplane will be propelled forwardly as this is the same condition as though we turned the sheet of drawings containing Fig. 5, upright, and the diagram may then be followed for forward flight.

30 It is thought that the construction, operation, utility, and advantages of the invention will now be clearly understood without a more detailed description thereof. The present embodiment of the invention has been disclosed in detail, because in actual practice it attains the features of advantage enumerated as desirable in the statement of the invention and the above description.

35 It will be apparent that changes in the details of construction, and in the arrangement and combination of parts may be resorted to without departing from the spirit or scope of the invention as hereinafter claimed or sacrificing any of its advantages.

40 Having thus described my invention, what I claim as new is:

In a propeller mechanism for vehicles comprising, a pair of hollow shafts journaled transversely through the vehicle body with 45 their inner ends disposed in spaced relation, means connecting with the inner end of said shaft for driving the same, an elongated frame secured to the outer end of each shaft, a pair of blades rotatably mounted on the 50 outer side of each frame, a solid shaft journaled through said hollow shafts, means between the inner ends of said hollow shafts for rotating said solid shaft, said blades being intergeared to the ends of said solid shaft 55 and adapted to be rotated thereby.

45 In testimony whereof I affix my signature.

ROBERT JEFFERSON CATLETT.
